UNITED STATES PATENT OFFICE

134,560

DESIGN FOR AN AIRPLANE CHAIR

Wendell S. Fletcher, Burbank, Calif., assignor
to Fletcher Aviation Corporation, Burbank,
Calif.

Application November 14, 1941, Serial No. 104,156

Term of patent 3½ years

To all whom it may concern:

Be it known that I, Wendell S. Fletcher, a citizen of the United States, residing at Burbank, in the county of Los Angeles and State of California, have invented a new, original, and ornamental Design for an Airplane Chair, of which the following is a specification, reference being had to the accompanying drawing, forming a part thereof.

Figure 1 is a side elevational view of an airplane chair, showing my new design;

Figure 2 is a front perspective view;

Figure 3 is a rear perspective view; and

Figure 4 is a bottom plan view thereof.

I claim:

The ornamental design for an airplane chair, substantially as shown.

WENDELL S. FLETCHER.
